UNITED STATES PATENT OFFICE.

PERCIVAL S. TICE, OF CHICAGO, ILLINOIS.

MIXTURE-GOVERNING DEVICE FOR INTERNAL-COMBUSTION ENGINES.

1,385,733.

Specification of Letters Patent. Patented July 26, 1921.

Application filed July 17, 1919. Serial No. 311,484.

To all whom it may concern:

Be it known that I, PERCIVAL S. TICE, a citizen of the United States, residing at Chicago, in the county of Cook and the 5 State of Illinois, have invented certain new and useful Improvements in Mixture-Governing Devices for Internal-Combustion Engines, of which the following is a specification, reference being had to the accompanying drawings, forming a part thereof.

The purpose of this invention is to provide an improved device for the purpose of governing the mixture supplied to an internal combustion engine through the carbureter. It consists in the elements and features of construction shown and described as indicated in the claims.

In the drawings:

Figure 1 is a section axial with respect 20 to the inlet of the portion of the intake passage of an engine equipped with this invention.

Fig. 2 is a modified form of the device, adapted to be interposed between the carbureter and the engine intake passage.

Fig. 3 is a section at the line C' on Fig. 1.

The present invention is designed to govern the mixture supplied to an internal combustion engine by governing the valve which 30 controls the inlet or suction passage so as to vary its opening by variation of the force of the suction due to varying speed of the engine. The invention here shown is an improvement upon or addition to the invention 35 shown in my Patent No. 1,305,820, dated June 3, 1919. The general type of construction of the inlet valve and its relation to the carbureter being substantially the same as that shown in said patent; and of these substantially identical features of construction 40 only a limited description will be here required.

In the drawings, Fig. 1 shows the present invention applied to the intake passage 45 of an engine having the intake passage in a substantially familiar form, said intake passage with the adjacent outline of the engine being shown at A, terminating in the opening through the boss, A¹, adapted to 50 have secured to it a fitting comprising the parts embodying the present invention. These parts comprise a body piece, B, which contains the inlet throat-way to the intake 55 passage. This throat-way or inlet passage is formed as shown, with a venturi-shaped inlet throat having its apex or constriction

at the transverse plane, C¹, of the hour-glass shaped throat-piece, C, which for convenience of construction is stamped or spun out of sheet metal and which is passed into 60 the cylindrical counter-bore, b¹, at the outermost end of the part, B, to the shoulder which is formed by said counter-bore b, and retained by a spring ring, C³, operating as a key, snapped into a groove, b², near the 65 outer end of the counter-bore. The inner wall of the inlet member, B, from the shoulder of the counter-bore to the inner end, is sloped or tapered in continuation of the slope of the inner end portion of the member, C, to complete the venturi form of the inlet throat. At the inner end of said venturi throat which extends to the inner end of said inlet fitting, B, there is provided a seat, b², for the valve, F, which is hollow 70 with a spheroidal outer end, F¹, and a substantially flat inner end, F², and which is made in two pieces in order to admit to its chamber a piston-wise operating member, G. This piston-wise operating member is carried rigidly at the inner end of a stem, H, which is situated axially with respect to the valve seat and venturi inlet throat. For holding it rigidly in this relation, it is preferably formed integrally with the fitting, 75 B, which has radial arms, H¹, extending inward to said stem, H. The spheroidal head, F¹, of the chambered valve, F, has its central aperture by which it is adapted to be entered on the guide stem, H, fitted with a 80 sleeve, f, which affords bearing for the sliding of the valve on said guide stem. Around said stem within the valve chamber, having one end seated upon the inner surface of the said spherical head, F¹, around the sleeve, f, 85 and the other end seated against the fixed piston-wise operating member, G, there is provided a spring, L, reacting between said piston-wise operating member and the valve, for normally holding the valve seated 90 on the seat, b², at the inner end of the inlet fitting, B, which is also the inner end of the venturi inlet throat. The guide stem, H, is utilized as an air inlet conduit affording atmospheric communication to the portion, f², of the total chamber in the valve 95 which is partitioned by the piston-wise operating member, G, into the two portions, f¹ and f², said portion, f², being on what may be called the "suction side" of said piston-wise operating member. For the purpose of serving as such conduit, the stem has

an axial duct, h , opening at the inner end opposed valve-influencing forces will become balanced at a certain stage of suction produced in the intake passage by the engine's speed; and that speed is thereby regulated as to its maximum. The adjustment of the 70 turn-cock valve, K, modifying the second factor (b) is therefore a means of fixing the maximum engine speed.

It is desirable in many cases to have the engine equipped for certain work requiring 75 maintenance of a certain known speed, and for that purpose it is desirable to have the engine equipped with the governing device, invariable as to the adjustment of the factor (b), so that it shall not be liable to be put 80 out of condition for greatest efficiency in the work to which it is applied. For this purpose the present invention may be embodied in the form shown in Fig. 2, in which the 85 intake passage of the device, including the valve chamber and the venturi inlet throat, is formed and contained in a body member which is adapted to be interposed permanently between the carburetor and the fixed 90 intake passage of the engine, and for that purpose has only substantially the necessary length to accommodate the valve and its 95 proper range of movement, and the venturi inlet throat, and which terminates at the opposite end in flat faced flanges adapting it 100 for securement at one end against the customary flat faced flange about the mouth of the engine intake passage, and at the other end to have secured to it a carburetor body provided with the usual flat faced flange for 105 attachment. In this Fig. 2 the operating parts are substantially as already shown, except that the turn-cock, B, is wanting, and said identical parts are indicated by the same characters applied to these parts in Fig. 1. 110 The intake body is shown composed of two parts, M and N, secured together substantially at the transverse plane of the valve, for convenience of inclosing the valve in the chamber between the two parts, the part, M, having at one end the flange, M¹, for securing the device to the terminal flange of the engine intake, X, and the part, N, having at the opposite end the terminal flange, N¹, for 115 securing the carburetor (not shown).

It will be understood that there must be substantial freedom of atmospheric communication with the chamber f^2 , and it will also be understood that the sleeve must move freely on the fixed stem in all movements of the valve; that is that friction between the parts at that point should be negligible. These two requirements are mutual, in that the necessary looseness of fit of the sleeve on the stem provides for the 120 necessary freedom of atmospheric communication. The air access around the stem at the bearing of the sleeve thereon is too slight to be indicated in the drawings without misleading exaggeration; but the fact 125 130

an axial duct, h , opening at the inner end beyond the piston-wise operating member, G, and at the outer end opening by means of a transverse passage, h^1 , in the venturi 5 inlet throat substantially at the transverse plane of the constriction,—that is, the plane, C¹. The other end of the stem, H, may be fitted with a valve device for regulating the air inlet to the duct, h ; and such valve devices in the structure represented in Fig. 1, 10 is of the general character of a turn-cock member, K, inserted in a counter-bore about the axial duct, H, at the outer end of the stem, H, said turn-cock member having two 15 ports, k , k^1 , diametrically positioned for registering with the opposite end portions of the cross port, h^1 , the lap of said ports, and consequent effective opening for atmosphere inlet, being adjusted by turning the turn-cock member 20 in its seat in the counter-bore mentioned; and for that purpose said turn-cock member has a lever arm, K², which may be connected in any convenient manner for operation either by hand or automatically from 25 some moving part, such connecting means not being shown in the drawings.

Independently of any means for manual or other automatic mechanical control of the atmosphere inlet afforded 30 by the duct, h , the degree of atmospheric pressure admitted through said duct to the cavity, f^2 , between the piston-wise operating member G, and the inner head of the chamber of the valve, is automatically 35 modified by the air current entering through the venturi inlet throat when the valve is open, by reason of the entrainment action of said air current passing the constriction of the venturi, tending to produce 40 a high vacuum at and just beyond the plane, C¹. This entrainment and partial vacuum operates suction-wise through the duct, h , to reduce the atmospheric pressure in the chamber, f^2 . Such reduction of pressure in 45 said chamber it will be understood, will operate contrariwise of the general suction operating of the valve for opening it against the resistance of the spring, L, thereby tending to diminish the opening of the valve 50 more as the in-drawn air current has a higher velocity. It will be seen, therefore, that the provision of the atmosphere inlet with its intake at the venturi constriction operates as an automatic governing means for 55 the valve, the suction which opens the valve being opposed by a resultant of that suction, viz., the back suction through the duct, h ,—plus the increasing resistance of the spring as the valve opens. The resultant opening- 60 opposing suction produced through the duct, h , is dependent upon two factors,—(a) the capacity of the duct, as determined by the degree of openness of the turn-cock valve K, and, (b) the air velocity at the venturi 65 constriction. With the first factor constant, the

of atmospheric access is indicated conventionally, by showing a leak-port f^{10} , in the outer wall of the valve. But, as above indicated, the actual presence of a leak-port other than that afforded by the free moving fit of the sleeve on the stem, is not required.

I claim:

1. In combination with a suction passage having a venturi-shaped inlet throat; a valve controlling the inlet seating outwardly at a seat located inward from the venturi constriction; a chamber and a member operating piston-wise therein co-operatively associated with the valve for relative movement of the said chamber and member in the seating and unseating movement of the valve, and a conduit leading into said chamber having one end opening within the venturi throat substantially at the transverse plane of the venturi constriction, and the other end opening in said chamber at the side of the piston member therein at which the cavity is enlarged by the opening movement of the valve; whereby the entrainment pull or suction operates on the valve counter to the direct suction of the engine.
2. In the construction defined in claim 1, the chamber being formed in the body of the valve, the piston-wise operating member being fixed in position; whereby the relative piston-wise operation is effected by movement of the chamber on said fixed member; a stem rigid with the intake passage wall

on which the valve moves, and which carries said fixed, piston-wise operating member, 35 the conduit for the venturi throat of the chamber being formed in said stem.

3. In the construction defined in claim 1, the two portions of the chamber into which it is partitioned by the piston-wise operating member therein, one on the side of approach to each other of said member and the chamber wall in the valve-opening movement, and the other on the side of approach in the valve-closing movement, having 40 bleeder or leak communications respectively, with the atmosphere and with the suction.

4. The structure defined in claim 1, formed with the wall or body of the suction intake 50 passage terminated at opposite sides of the valve and venturi inlet throat respectively with means for joining it at said opposite sides respectively to a further intake to the engine to be served and to a carburetor; 55 whereby the device comprising the valves and venturi and the inclosing and sustaining wall constituting intake passage, is adapted to be permanently interposed between and secured to the carburetor and the engine intake.

In testimony whereof, I have hereunto set my hand at Chicago, Illinois, this 14th day of July, 1919.

PERCIVAL S. TICE.
